UNITED STATES PATENT OFFICE.

ALBERT S. SAMUELS AND JACOB RITTIGSTEIN, OF SAN FRANCISCO, CALIFORNIA.

POCKET SALES-REGISTER.

1,323,494.

Specification of Letters Patent.

Patented Dec. 2, 1919.

Application filed April 23, 1917. Serial No. 163,784.

To all whom it may concern:

Be it known that we, ALBERT S. SAMUELS and JACOB RITTIGSTEIN, citizens of the United States, and residents of the city and county of San Francisco, State of California, have invented a new and useful Pocket Sales-Register, of which the following is a specification.

Our invention relates to sales registers. 10 An object of our invention is to provide a sales register adapted to be carried in the pocket of the clerk using it.

Another object of our invention is to provide a sales register which will prevent dishonest handling of money received from customers.

The invention possesses other features of advantage, some of which, with the foregoing, will be set forth in the following description of the preferred form of our invention which is illustrated in the drawings accompanying and forming part of the specification. It is to be understood that we do not limit ourselves to the showing made by the said drawings and description, as we may adopt variations of the preferred form within the scope of our invention as set forth in the claims.

Referring to the drawings.

Figure 1 is a perspective view of the pocket sales register of our invention.

Fig. 2 is a vertical section taken lengthwise of the register.

Fig. 3 is a vertical section of the register taken on the line 3—3 of Fig. 2.

Fig. 4 is a perspective view of a portion of the register.

Fig. 5 is a section taken on the line 5—5 of Fig. 2.

The sales register of our invention consists of a rather thin, flat, metallic casing 4 of such size and proportions as to slip easily into the salesman's coat pocket or an apron pocket if the clerk be a woman. The question of size is a very important consideration, since it is essential in fixing personal responsibility upon each individual that his register be of such size that it is conveniently carried upon his person. The casing 4 is provided with a cover 5 preferably hinged thereto at one of the long sides 6, and the cover is provided with a hinged hasp 7 in which is arranged a lock 8 for securing cover and casing together.

At one end of the casing the walls are apertured to receive a spindle 9 threaded at

one end and having a knurled thumb nut 10 at the other end. The spindle is adapted to hold a magazine roll 12 comprising triplicate strips S', S² and S³ of sales checks 60 wound on a suitable core.

At the end of the casing opposite from the magazine roll is mounted a resilient feed roll 13 which is operated by the thumb wheel 14. Mounted in the cover immediately above the roll 13 is a second resilient feed roll 16 which is brought into operative relation with roll 13 when the cover is closed. Lying between the magazine roll and the feed rolls is a platen 17 across which 70 the triplicate strips of sales checks pass. Preferably the platen is hinged to the casing in the same line with the cover and at the opposite side is supported by the flange 18 formed on or in the casing 4. Both long 75 sides of the platen are turned downwardly to form flanged edges 17^a and 17^b and this positions the body of the platen closely adjacent the cover 5. An aperture is formed in the cover so that the sales check exposed 80 upon the platen may be written on.

In order to keep the sales check strips smooth and tight upon the platen, means are provided for frictionally resisting the passage of the strips across the platen and this means consists of flat springs 21 affixed to or integral with the body of the platen and pressing against the under side of the cover. The platen is arranged to lie close to the cover and when the sales check strips are 90 passed between cover and platen the springs 21 frictionally resist the movement so as to keep the strips in slight tension.

Means are provided for holding two sheets of transfer paper between the check strips. 95 Extending along each long edge of the platen are a series of short, shallow grooves 22, and formed on the under side of the cover are corresponding beads 23 adapted to lie in the grooves when the cover is closed. When a 100 fresh magazine roll is placed in the casing, suitably sized sheets of carbon paper are laid across the platen between the check strips and extending on both sides over the grooves. When the cover is closed the beads press the 105 paper into the grooves and clamp it securely in place.

The upper two sales check strips S' and S² are arranged to be discharged from the machine, one check for the cashier and one 110 for the customer. The third and lower strip S³ is retained in the casing for the use of

the cashier in checking the transactions. The end of the cover opposite the feed roll 13 and the adjacent edge of the casing are formed into narrow lips 24 providing a slot 5 through which the cashiers' and customers' checks are discharged from the machine. The end of the casing adjacent the feed roll 13 is curved so as to direct the secret strip S³ back into the casing where it accumulates under the platen. Interference with the magazine roll by the folds of the accumulating secret strip is prevented by a partition 26 extending across the casing in front of the magazine roll. Preferably we 15 form this partition as an integral portion of the platen 17.

It is contemplated that only the cashier or other official will have access to the inside of the pocket registers, and further that 20 the registers will be deposited with the cashier when the clerk leaves the store. The registers preferably bear a number such as indicated at 27 identifying the register with the particular individual who alone is to 25 use it.

To insert a magazine roll in the pocket register, the cover and platen are turned back and the magazine roll set in position. The spindle 9 is then inserted and screwed 30 home and the platen turned down into place. The bottom strip S³ is next laid across the platen and around the feed roll 13, the end being thrust down between the roll and the end of the casing. A sheet of transfer paper 35 is then laid transversely across the strip S³, and the strip S² followed by another sheet of transfer paper and the strip S' is laid down upon the first strip, the two strips S' and S² extending out over the roll 13. 40 The cover is now closed and locked, clamping the edges of the transfer paper so that the sheets cannot move when the strips are fed forward; and bringing the roll 16 into operative relation with the roll 13, so that a turning of the thumb 45 wheel 14 effects a tractive effort upon the strips. Preferably the surfaces of both rolls are formed of rubber or comparable material and the diameter is preferably 50 slightly greater at the ends so that the rolls contact with each other at each end. This is to insure the proper and uniform feeding of all of the strips.

Instead of two transfer sheets arranged 55 between the three sales check strips, we may prefer to use but one double-faced transfer sheet disposed between the strips S² and S³, making the strip S² of transparent material so that the carbon impression upon the back 60 may be read in the usual manner.

It will be understood that since the magazine roll 12 revolves freely on the spindle

9, there is no way in which the magazine roll in the locked casing can be turned to wind up the strips once they have been unrolled. A ratchet mechanism of the usual well-known type may be incorporated if desired, to prevent a rewinding of the strips, but the free rotation of the roll upon the spindle is deemed sufficient to guard against 70 this.

We claim:

1. A pocket sales register, comprising a casing, a platen arranged in said casing and having a down-turned end adapted to form 75 a partition across said casing, means for supporting said platen in said casing, a cover for said casing having an aperture therein above said platen and means for feeding sales check strips across said platen, 80 said casing having a curved wall for directing one of said strips rearwardly under said platen against said partition.

2. A sales register, comprising a casing of a size adapted to fit in a coat pocket, a 85 cover for said casing having an aperture therein, a platen below said aperture, means for supporting said platen in said casing, lips formed on adjacent edges of said cover and casing to form a slot therebetween, a 90 feed roller mounted in said cover adjacent said lips, a second feed roller adapted to contact with the first-named feed roller mounted in said casing, means at the opposite end of said casing for holding a magazine roll, springs on said platen arranged to bear against the cover, and means for securing the cover to said casing.

3. A pocket sales register, comprising a 100 casing, an apertured cover hinged to said casing, a platen hinged to said casing and lying below the aperture in said cover, means for supporting the free end of said hinged platen, springs on said platen adapted to press against said cover, and 105 means for preventing the opening of said cover.

4. A sales register, comprising a flat casing, a cover for said casing having an aperture therein, a platen below said aperture, 110 a magazine roll of sales check strips arranged at one end of said platen in said casing, and a feed roll at the other end of said platen in said casing, the wall of said casing adjacent said feed roll being curved, whereby one of said strips is directed around said roll and below said platen.

In testimony whereof, we have hereunto set our hands at San Francisco, California, this 9th day of April, 1917.

ALBERT S. SAMUELS.
JACOB RITTIGSTEIN.

In presence of—
C. S. EVANS.
